(57) **CLAIM**

We claim the ornamental design for an orb pet water fountain, as shown and described.

DESCRIPTION

FIG. 1 is a perspective view showing a new design for the orb pet water fountain. An orb rests inside of a bowl.

FIG. 2 is a front view of the water fountain of FIG. 1.

FIG. 3 is a back view of the water fountain of FIG. 1, which is opposite the view of FIG. 2.

FIG. 4 is a right side view of the water fountain of FIG. 1.

FIG. 5 is a left side view of the water fountain of FIG. 1, which is opposite the view of FIG. 4.

FIG. 6 is a top or plan view of the water fountain of FIG. 1.

FIG. 7 is a bottom view of the water fountain of FIG. 1; and, FIG. 8 is an exploded perspective view of the water fountain of FIG. 1. The orb is shown above the bowl, revealing items of hardware inside the bowl.

The features shown in broken lines and portions contained within broken lines depict portions of the orb pet water fountain that form no part of the claimed design, and are not claimed.
